UNITED STATES PATENT OFFICE.

THOMAS D. LOCKWOOD, OF MELROSE, MASSACHUSETTS.

ELECTRO-MAGNETIC SHUNT FOR TELEPHONE-RECEIVERS.

SPECIFICATION forming part of Letters Patent No. 393,165, dated November 20, 1888.

Application filed August 10, 1888. Serial No. 282,407. (No model.)

To all whom it may concern:

Be it known that I, THOMAS D. LOCKWOOD, of Melrose, in the county of Middlesex and State of Massachusetts, have invented certain 5 Improvements in Electro-Magnetic Shunts for Telephone-receivers, of which the following is a specification.

This invention relates to means for relieving telephone-instruments from the pernicious 10 and disturbing effects of induction from other circuits. It is especially serviceable in cases where the said disturbing effects accrue from circuits carrying electric-light and power currents.

15 The invention is based upon the well-known fact in applied electricity that telephonic electric currents, by reason of their rapid rate of change per unit of time, pass through electro-magnetic helices with great difficulty and with 20 considerable loss of volume and power. This phenomenon is of course due to the counter magneto-electric currents which are set up in the electro-magnet coil, and which flow to the main circuit at every change in the telephonic 25 current. Since these changes occur at the rate of about twenty-eight thousand per second of time, and since a counter-current is developed at each change, it follows that an ordinary electro-magnet is in no inconsiderable 30 degree opaque to telephonic or voice currents. It is also based upon the electrical axiom that when two routes are open to a current of electricity under ordinary conditions the said current will divide between them in the inverse 35 ratio of their resistances or directly as their respective conductivities. Heretofore attempts have been made to reduce the disturbances due to induction by shunting the receiving-telephone by a derived circuit of 40 suitable resistance. It has, however, invariably been found that while the induction was indeed diminished the legitimate or voice current was also diminished and in a like proportion, and thus the gain in comparative 45 freedom from disturbance was in a great measure counterbalanced by the loss in the volume or strength of the reproduced conversation. By the employment of my invention I provide 50 that the disturbing current shall be practically dissipated or led off by a by-path, while the

voice-currents are caused to pass through the telephone - helix without suffering material diminution. This I accomplish by shunting the receiving-telephone with a properly-proportioned electro-magnet, by providing that 55 this shunt shall preferably be formed of an earth branch; that it shall be derived from the main line at a point between the secondary helix of the induction-coil and the helix of the receiving-telephone, the induction-coil being 60 located in the circuit with the most advantage outside of or external to the receiving-telephone, and by introducing resistance into the telephone branch of sub-stations so provided.

Figures 1 and 2 are diagrams indicating successive steps in the history of the invention. Fig. 3 is a diagram of a line fitted with the induction-suppressor at three stations. Figs. 4 and 5 are respectively a cross-sectional elevation and a perspective view of the peculiar 70 form of the electro-magnetic shunt which I employ or may employ, and which, in combination with a telephonic receiver, constitutes a special feature of my invention; and Fig. 6 is a cross-section of a modification thereof. 75

In Figs. 1, 2, and 3, *w* represents a telephone-line, while *W* in Fig. 1 represents a wire carrying electric-light or power currents, exercising induction upon the telephone and producing a loud musical sound in the receiving-telephones, whereby the reproduction of speech is greatly interfered with. This wire *W* is not shown in the other figures, although its presence is to be assumed. The receiving-telephone *t* and the transmitting-telephone *t'* are in the 80 telephone-circuit which terminates at the earth *G*. From a point, 4, on the line *w* a branch, derived, or shunt circuit, *a*, is led to earth at *G*, passing through an electro-magnet so constructed as to have a very high coefficient of 85 self-induction, while it may be of comparatively low resistance relatively to the resistance of the telephone branch or extension *T*. An ordinary or steady electric current flowing in the circuit *w* would of course divide at 90 the point 4 inversely in the ratio of the resistances of the two branches *T* and *a*, regardless of other conditions; but with a telephonic current which is constantly and with great frequency changing in character the case is dif- 95 100

ferent. The introduction of the electro-magnet *b* into the derived circuit *a* makes the said derived circuit practically impervious to the telephonic current of the main line, for reasons hereinbefore stated. Consequently I am enabled to construct the electro-magnet *b* with comparatively coarse wire, offering but a very low resistance relatively to the total resistance of the telephone-extension *T*. Notwithstanding this low resistance, however, very little of the legitimate telephonic current will leak away by this route to earth by reason of the imperviousness to such currents which I have described, this being due to the self-induction of the electro-magnet, or, in other words, to the counter-currents generated in the coils by the continuously-magnetic variation of the core effected by the passing voice-currents.

While the disturbing induced currents are not absolutely constant and uniform, and do not, therefore, pass the electro-magnet with as great a facility as if they were constant, still their frequency of change is greatly below that of the telephonic currents, as may be demonstrated from the pitch of the musical sound which they produce in the telephone. As a consequence, they are to a much greater extent amenable to the general law of derived circuits which I have hereinbefore stated, and the portion of the entire disturbing current which leaks away over the derived circuit is a much greater fraction of the whole than can be the case with the telephonic current. Thus I am enabled to subdue to a great extent the undesirable noises of the telephone without any appreciable diminution of volume in the reproduced speech; and I have found in practice that in each individual case the resistance and self-induction of the shunting-magnet *b* can without difficulty be so proportioned that the disturbance can be subdued to such a degree as to be scarcely perceptible, while the telephonic current is apparently undiminished in power. Moreover, the electro-motive force of the induced or disturbing current is not so high as is that of the telephonic current; hence it loses much more in strength by the interpolation of resistance.

The arrangement shown in Fig. 1 has been found an effective suppressor of induction; but it is evident that it materially interferes with the efficiency of the transmitter when the latter is placed as shown, for, while the derived circuit *a* does not materially depreciate the power of the receiving-telephone as regards voice-currents, it seriously cripples the power of the transmitter; and this was to be expected, because the leak through the magnet to earth intercepts the current generated by the transmitter, it being a much shorter circuit from the junction-point through the derived circuit than over the line, while the incoming current, which is required to act on the receiver, does not strike the divergent route

through the shunt-circuit until the line constituting the greater portion of the circuit is passed over, so that, even though the said shunt-circuit were a simple resistance, very little, comparatively, of the said current would be lost. But it is now clear that it is not necessary to shunt both transmitter and receiver. It is the latter appliance only which requires protection from the induced currents, and I find it then convenient and preferable to connect the appliances, as in Fig. 2, in which the transmitter-circuits are drawn in detail. The transmitter connects with the main line through the secondary helix *c* of an induction-coil, *f* being the primary helix thereof, (in circuit with the transmitter proper, *t*), and the local battery *d*, *r* being the iron core. The derived circuit is in this figure and in practice connected with the line at a point between the secondary coil *c* and the receiving-telephone *t*, the transmitter-coil being in the outward position—that is, included in the circuit in a position nearer than the receiver to the external portion of the line. So connected, the result is that the noise is hushed down, as in the former case, the major part of the disturbing current leaking away through the shunt. The telephone-current is not materially lessened, any slight depreciation in volume being fully made up by increased sharpness and by the quietness of the line, and, the secondary transmitter-coil being now uncontrollable by the shunt, the power of the transmitter is now actually greater than when connected as usual.

I account for the fact that the power of the transmitter is actually increased under the above conditions in the following manner: In the first place, the two branches in the rear of the transmitter-coil furnish two routes to earth, and thus effectually guarantee that the resistance of the earth-terminal of the line shall be kept down; and in the second place a telephone-transmitter coil so located has a greater tendency to propagate the impulses it develops in a forward direction, because the two routes in its rear both include an electro-magnetic coil, and therefore both act as a dam upon the current in the direction of the ground end. It is therefore a decided advantage in several ways to branch the shunt-wire from a point between the transmitter and receiver coils and to provide that the former shall be outermost.

In Fig. 3 is represented a line having three stations, two of which, 1 and 3, are terminal, while one, 2, is way. It is obviously impracticable to establish an earth-shunt including a suitable electro-magnet at way stations. Therefore, although, for reasons hereinbefore stated, an earth branch or shunt is to be preferred, I employ at way-stations a loop-shunt round the telephone-helix only. The said shunt extends from a point, 4^a, through the electro-magnetic shunt *b* to a point, 4^b, on the other side of the telephone *t*. In order that

during the day-time, when electric-light induction is not ordinarily prevalent, the shunt may, if desired, be thrown off for the purpose of obtaining the full value of the telephone, I 5 provide a switch, *s*, in the shunt-circuit.

In some cases, where the electric-lighting current is generated by dynamos rotating at a very high rate of speed, it is found that the rate of change per unit of time of the induced 10 current is also much higher. This of course brings the said rate nearer to that of the telephonic current. When this occurs, it becomes necessary to provide an electro-magnetic shunt, *b*, the resistance whereof is materially 15 lower than would otherwise be required. When the said shunt is so low that a further reduction would too greatly weaken the telephone-current, availing myself of the well-known fact that the said telephone-current has 20 a very high electro-motive force, and is thus practically unaffected by the introduction of simple resistance-coils without iron cores, I introduce resistance-coils *f*, wound differentially to avoid self-induction, into the telephone branch; and I find that in practice this 25 achieves the desired end and diminishes the induction-currents in a much greater degree than it does the legitimate or voice currents.

In Figs. 4 and 5 is shown one form of electro-magnet well adapted for inclusion in the 30 derived circuit which I have described. It is composed of two spools, *h*, of insulated wire *i*, the helices of the two being connected in series. Each has a soft-iron core, *j*, and the said 35 cores are united at both ends by iron plates *g* and *k*, thus (if we may so speak) closing the magnetic circuit. Each spool also has an inclosing-case, *x*, of iron. I have attained good 40 results by the use of this coil. Instead, however, of uniting the cores of the two coils by iron cross-bars or yokes, I may provide simply 45 separate iron disks, *m*, at each end of the two coils, as in Fig. 6. When this is done, a convenient way is to form one of the said disks integral with the inclosing iron sheath *x* and to fasten the other to the core, which may then be slid in and out of the coil to regulate the 50 inductive power of the appliance in a manner well understood. When the form of coil shown in Fig. 6 is adopted, one or more may be used, connected in series, as any special case may require.

In practice with the average telephone-line I have found the best results, both with respect 55 to the reduction of disturbance and the maintenance of the efficiency of the talking, to accrue from a small and short coil measuring about ten ohms resistance, provided with an iron external sheath, iron disks inclosing the 60 ends, and a solid iron core, the said coil being about one and a half inch long and one and one-eighth inch thick externally. This coil was wound with No. 26 Brown & Sharpe silk-covered wire.

65 I am aware that patent of S. P. Thompson,

No. 327,837, dated October 6, 1885, describes the use of a shunt around an electro-magnetic telephone in circuit with a battery for the purpose of increasing the sensitiveness of such a telephone, said shunt including a resistance 70 of such nature as to oppose the passage of the voice-currents, while offering practically no opposition to the steady battery-currents. The arrangement shown in Fig. 1 of the present application is, however, regarded as a novel 75 expedient for suppressing induced currents when the telephone-circuit is in proximity to a disturbing wire.

Having thus described my invention, I 80 claim—

1. The combination, in a telephone-circuit, of a transmitting-instrument operating upon the main line by means of an induction-coil having its secondary helix included in the circuit of said main line, a receiving-telephone 85 also in said circuit, and a derived circuit to earth, including an electro-magnet branching from said main line at a point between the secondary helix and the receiving-telephone helix, substantially as described. 90

2. In a telephone-circuit, the combination, substantially as hereinbefore described, of a telephone-transmitter, a telephone-receiver, and a derived circuit to earth, including a suitably constructed and proportioned electro-magnet, the said transmitter being connected with the main circuit at a point external to or nearer the line than the receiver, and the said derived circuit being branched from the main circuit at a point between the transmitter and 100 receiver. 95

3. In a telephone-circuit, and in combination with the line and the transmitter and receiver in said line, a derived circuit branched from the line between the receiver and transmitter and shunting the receiver, and an electro-magnet in said derived or shunt circuit, substantially as described. 105

4. In a grounded telephone-circuit, and in combination with the main line, the transmitter in said line, and the receiver also in said line between the transmitter and the ground, a derived circuit branched from the line between the receiver and transmitter and shunting the receiver, substantially as described. 110

5. A telephone-circuit and a transmitter and receiver included therein at the several stations thereof, an electro-magnetic shunt, substantially as specified, around the receiver only and not around the transmitter, and a 115 switch in circuit with the said shunt for the purpose of disconnecting the same when required.

6. The combination, at a telephone-station, substantially as hereinbefore described, of a 120 main circuit, a shunt or derived circuit, a receiving-telephone common to and included in both circuits, and an electro-magnetic appliance comprising one or more spools of insulated wire surrounding iron cores and inclosed 125 130

in iron envelopes in the said shunt-circuit, the said spools being of lower total resistance than that of the telephone-helix.

7. The combination of a main telephone-circuit, a receiving-telephone, and a resistance or rheostat included therein, and a derived circuit shunting the said telephone and resistance, substantially as and for the purposes specified.

In testimony whereof I have signed my name to this specification, in the presence of two subscribing witnesses, this 28th day of July, 1888.

THOS. D. LOCKWOOD.
